UNITED STATES PATENT OFFICE

117,068

DESIGN FOR A COMBINATION CARD AND BOWL COVER DISPLAY

Michael Laitman, Brooklyn, N. Y.

Application April 17, 1939, Serial No. 84,337

Term of patent 7 years

To all whom it may concern:

Be it known that I, Michael Laitman, a citizen of the United States, resident of Brooklyn, in the county of Kings and State of New York, have invented a new, original, and ornamental Design for a Combination Card and Bowl Cover Display, of which the following is a specification, reference being had to the accompanying drawing, forming part thereof.

I claim:

The ornamental design for a combination card and bowl cover display, as shown.

MICHAEL LAITMAN.
